The ornamental design for a cable organizer, as shown and described.

DESCRIPTION

FIG. 1 is a front perspective view of a cable organizer showing, in particular, the ornamental design thereof;

FIG. 2 is a top plan view of the cable organizer of FIG. 1; FIG. 3 is a bottom plan view of the cable organizer of FIG. 1; FIG. 4 is a left side elevation view of the cable organizer of FIG. 1. It will be understood that a right side elevation view will be a mirror image of the left side elevation view; and, FIG. 5 is a front end view of the cable organizer of FIG. 1. It will be understood that a rear end view will be a mirror image of the front end view. The broken lines in the drawings represent unclaimed environmental subject matter.

The broken lines in the drawings represent the boundaries of the claimed design. The broken lines form no part of the claimed design.
